UNITED STATES PATENT OFFICE

2,052,644

RUBBER HEATING UNIT

Morton Murphy, Indianapolis, Ind.

Application November 12, 1934, Serial No. 752,656

1 Claim. (Cl. 219—46)

This invention relates to electrical means for applying heat to various parts of one's body. A primary object of the invention is to provide means whereby an electrical heating element may be employed to be placed in close proximity to the skin without the danger of electrical burns or shock should the carrier of the element become wet or should the element break within the carrier. Electrical heating pads have been employed for some time wherein the element was carried within some cloth or textile member and such a pad has become to be recognized as dangerous in that a slight moistening thereof places the electrical circuit in direct connection with the user and furthermore should the circuit develop, there is great danger of fire. The heating element must be flexible in order to permit the pad to conform to the contour of the surface to which it is applied and this means that the element is subjected to much bending which in itself tends to wear out the element and cause it to break.

My invention consists essentially in embedding a resistance wire of relatively small diameter within rubber so that the element is at all times electrically insulated as well as being entirely enclosed and covered over against the entrance or access thereto of moisture. By means of the rubber carrier, particularly in the form of a heating pad, the pad is flexible so as to permit its conforming to the contour of the surface over which it is applied. Another advantage of my invention is that it may be manufactured at a relatively low cost and still preserve the objects and advantages above indicated with perfect safety to the user.

Further objects and advantages of the invention will become apparent to those versed in the art in the following description of the invention as illustrated by the accompanying drawing, in 40 which

Fig. 1 is a top plan view of a pad embodying my invention with part of the upper surface broken away;

Fig. 2, a vertical transverse section on the line 2—2 in Fig. 1;

Fig. 3, a front elevation of a pad embodying my invention in a modified form;

Fig. 4, a vertical transverse section on the line 4—4 in Fig. 3;

Fig. 5, a top plan view of the form shown in Fig. 3;

Fig. 6, a vertical elevation in partial section of a heating unit for internal use, and

Fig. 7, a transverse section on the line 7—7 in Fig. 6.

Like characters of reference indicate like parts throughout the several views in the drawing.

Referring first to the form of the invention as illustrated in Figs. 1 and 2 showing a heating pad, I take a sheet 10 of uncured rubber and press it down over a plurality of pins 11. These pins 11 are properly located so that a length of resistance wire 12 may start by one end as at 13 and then be carried therearound to form loops on one side of the center line and then carried across 10 and around under those loops to the other side and looped back and forth to be carried around by its other end 14 to terminate adjacent the first end 13. Conducting wires 15 and 16 are connected to the respective ends 13 and 14, these 15 wires 15 and 16 being preferably embedded and covered by rubber to form the customary rubber insulated cable. This cable is so placed as to have the rubber insulation thereof lapped over on the sheet 10 adjacent the wire ends 13 and 14. I then 20 apply a second sheet of uncured rubber 17 over the resistance wire 12 and press it down firmly over the pins 11 and the wire 12. Preferably, although not necessarily so, a third sheet of uncured rubber 18 is laid over the sheet 17. The 25 assembly thus arranged is lifted from the pins 11 and placed in a suitable vulcanizer wherein the sheets are subjected to pressure one against the other while heat is applied so that the sheets may be brought into intimate contact and vulcanized 30 one to the other to form in effect a resultant single thickness of rubber within which the resistance wire 12 is embedded nearer one outer surface than the other.

The resistance wire 12 is preferably in a coiled form, although not necessarily so. The coiled form is preferred on account of the fact that it permits of a more flexible pad and when the pad is folded or twisted around, the wire itself is not so likely to break. The relative thicknesses of 35 the sheets 10, 17 and 18 as indicated in Fig. 2 are somewhat exaggerated in the drawing in order to clearly show the structure. The sheet 17 overlaps the rubber insulation of the cable including the wires 15 and 16 so that the end of 40 the cable is vulcanized between the sheets 10 and 17 to have its insulation become an integral part thereof. By reason of the single sheet 10 on one side and the two sheets 17 and 18 on the 45 other side of the heating wire, the pad at once provides "two heats". That is on the side of the pad having but the one sheet 10 covering the wire 12, more heat will be transmitted than on the other side where two sheets cover the wire 50 55

12. Thus by merely turning the pad over, the application of heat may be varied.

In the form of the invention as shown in Figs. 3-5, I have provided a pad 19 here shown as having a marginal forwardly projecting flange 20 with a cable 21 leading from the center. The pad 19 is formed in the same manner as above described in reference to the pad shown in Figs. 1 and 2 to have a heating element 22 embedded within rubber. The pad 19 is so formed as to proportions and dimensions that it may be inserted within a patient's mouth to have the upper portion of the pad in contact with the upper teeth and gums and the lower part in contact with the lower teeth and gums. The pad in use assumes the shape somewhat as indicated by the dash lines in Fig. 5, the pad being sufficiently flexible and elastic to permit its being inserted between the cheeks and the teeth. The marginal flange 20 serves to space the cheeks away from the pad and thereby prevent undue heating or burning of the cheeks, thus permitting without discomfort, an application of heat at a temperature well above body heat to the patient's gums. Where heat is to be applied internally, the resistance wire 23, Figs. 6 and 7, may be wound about an uncured rubber core 24 and then a sheet of uncured rubber 25 wrapped therearound and vulcanized to the core 24 within a suitable mold so as to form an integral rubber carrier with the heating wire 23 relatively close to the outer surface. The rigidity of the unit is determined by the rubber mixture employed.

It is to be seen that in any one of the above indicated forms which are only a few of the possible many forms the invention may assume, the heating element is directly embedded within a rubber carrier to have the element close to at least one side thereof, but thoroughly insulated against moisture as well as electrically so that the pad or heating unit will be used in perfect safety under all conceivable conditions. I find that

by properly proportioning the heating element in the various units, I can secure a transmission of heat of desired amount without in any way affecting the rubber carrier. It is of course essential to have a sufficient amount of wire in the heating element so that no local area thereof becomes heated to that temperature which will damage the surrounding rubber. The heating element is directly embedded within the rubber without any intervening fabric or other insulating medium. Since the cable leading the conducting wires from the heating unit is molded and vulcanized in the unit to become an integral part thereof, there is no danger of break-down or water leakage at the connection of the cable with the unit.

While I have herein shown and described my invention in the form now best known to me, it is obvious that structural changes may be made without departing from the spirit of the invention and I, therefore, do not desire to be limited to that precise form beyond the limitations as may be imposed by the following claims.

I claim:

A flexible elastic heating pad comprising a length of spirally wound resistance wire looped between two sheets of rubber vulcanized one to the other to extend between the spiral windings and loops of the wire, said wire being in direct contact with the rubber and stretching therewith by reason of said spirally wound arrangement, said wire being wrapped around a plurality of pins located so that a length of wire starts at one end of the pad and is carried thence around forming loops on one side of the center line of the pad and then carried across the pad under these loops to the other side of the pad and looped back and forth to form loops on the other side of the center line of the pad and terminating adjacent the first end.

MORTON MURPHY.
